Primary Examiner — Philip S Hyder(74) *Attorney, Agent, or Firm* — Antero Tormey Petrin;
Pete Tormey(57) **CLAIM**

The ornamental design for a sanding block, as shown and described.

DESCRIPTION

FIG. 1 is a front perspective view of a sanding block, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict portions of the sanding block in which the design is embodied that are not considered part of the claimed design.

1 Claim, 7 Drawing Sheets(56)
